UNITED STATES PATENT OFFICE.

JOHN P. SCHNEIDER, OF CHICAGO, ILLINOIS.

EYE-SHADE.

1,110,350.

Specification of Letters Patent. Patented Sept. 15, 1914.

Application filed August 27, 1913. Serial No. 788,864.

To all whom it may concern:

Be it known that I, JOHN P. SCHNEIDER, a citizen of the United States, residing at Chicago, in the county of Cook and State 5 of Illinois, have invented certain new and useful Improvements in Eye-Shades, of which the following is a full, clear, concise, and exact description, reference being had to the accompanying drawings, forming a 10 part of this specification.

My invention relates to eye shades and its object is to provide an improved device of this character which can be economically manufactured.

15 The embodiment of my invention, herein-after described in detail and subsequently claimed, comprises a vizor provided with backwardly projecting bands arranged to encircle the head of the wearer to prevent lateral displacement of the vizor. Secured to the rearwardly projecting bands just mentioned are other bands arranged to extend over the top of the head of the wearer and so prevent downward displacement of the 20 vizor. The vizor and the several bands before mentioned are preferably made of celluloid or some other light and flexible material. Connecting the straps for preventing the downward displacement of the 25 vizor and the rear edge of the vizor is a relatively stiff strap, preferably of metal, which spaces the rear edge of the vizor from the forehead of the wearer of the eye shade and thus does away with the annoyance which would result from having the 30 vizor engage the forehead.

The several elements of the device of my invention are adjustable in order that the device may be adapted for use by different 35 persons.

These and other features of the device of my invention are set forth in detail in the accompanying description and are illustrated in the accompanying drawings in 40 which—

Figure 1 is a side elevational view illustrating the eye shade of my invention in place upon the head of a wearer, and Fig. 2 is a fragmentary plan view illustrating 45 the vizor, the straps which prevent downward displacement of the vizor and the strap which retains the rear edge of the vizor out of engagement with the forehead of the wearer.

50 In the drawings, at 3 I have illustrated a vizor, preferably of celluloid or some other

equivalent light and flexible material, said vizor being provided with a pair of bands or straps 4 formed integral with the vizor, said bands being arranged to encircle the 60 head of a wearer to prevent lateral displacement of the vizor and having their rear ends secured together by means of a suitable clip or fastener 5.

Fastened to each one of the straps 4 by 65 means of a clip or fastener 6 is one of a pair of straps 7 arranged to be secured together by means of a clip or fastener 8, these straps extending up over the top of the head of the wearer and so preventing downward displacement of the vizor. The clip 8 extends through registering apertures in the straps 7 and so secures the adjacent ends of the straps together. A loop 9 may, if desired, be provided for holding adjacent 70 faces of the straps snugly together when they are overlapped, as shown in the drawings. The clip 8 also passes through a suitable one of a number of apertures formed in one end of a relatively stiff strap 10, preferably of sheet metal, the other end of which strap is fastened by means of a clip or fastener 11 to the rear edge of the vizor 3. This strap 10, as clearly shown in Fig. 1, 75 spaces the rear edge of the vizor from the 80 forehead of the wearer. This strap at the same time assists the straps 7 in preventing the downward displacement of the vizor.

It will be noted that a plurality of apertures are provided in the straps 4, 7 and 10 85 in order that the vizor may be readily adjusted to suit the requirements of any 90 wearer.

What I claim and desire to secure by Letters Patent of the United States is:

1. In an eye shade a vizor in combination with means for preventing lateral and downward displacement of the vizor comprising a band adapted to pass over the head of a wearer from side to side, and a 100 relatively stiff strip connecting said band with the rear edge of the vizor adapted to space the rear edge of the vizor from the forehead of the wearer.

2. In an eye shade a vizor in combination 105 with a band attached to the vizor adapted to extend around the head of a wearer to prevent lateral displacement of the vizor, a second band having its ends attached to the first band adapted to pass over the head of 110 a wearer from side to side to prevent downward displacement of the vizor, and a rela-

tively stiff strip connecting the second band with the vizor and adapted to space the rear edge of the vizor from the forehead of the wearer.

3. In an eye shade, a vizor in combination with means for preventing lateral and downward displacement of the vizor comprising a band adapted to pass over the head of a wearer from side to side, and a relatively stiff metal strip connecting said

band with the rear edge of the vizor adapted to space the rear edge of the vizor from the forehead of the wearer.

In witness whereof I hereunto subscribe my name this 25th day of August, A. D., 1913.

JOHN P. SCHNEIDER.
